UNITED STATES PATENT OFFICE.

JAMES D. RANDALL, OF CINCINNATI, OHIO, ASSIGNOR TO THE J. D. RANDALL COMPANY, OF CINCINNATI, OHIO, A CORPORATION OF OHIO.

BELT FINISHER.

Application filed June 7, 1921. Serial No. 475,800.

To all whom it may concern:

Be it known that I, JAMES D. RANDALL, a citizen of the United States of America, and a resident of Cincinnati, in the county 5 of Hamilton and State of Ohio, have invented a new and useful Improvement in a Belt Finisher, of which the following is a specification.

An object of my invention is to provide 10 a device adapted to smoothly round the edges of belts and to color, burnish and enamel the rounded edges after their formation.

Another object is to provide a device for 15 the purpose stated that is simple in construction and operation and that will do the specified work with the maximum efficiency.

These and other objects are attained by 20 the means described herein and disclosed in the accompanying drawings, in which—

Fig. 1 is a plan view of a device embodying my invention.

Fig. 2 is a sectional view on line 2—2 of Fig. 2.

Fig. 3 is an inverted plan view of the device shown in Fig. 2.

Fig. 4 is an enlarged sectional view on line 4—4 of Fig. 1.

My invention comprises a table over 30 which belts are moved longitudinally of their length and suitable cutters, brushes and burnishers adapted to operate upon the side edges of the belt, together with mechanism to actuate the belts and the 35 mechanisms operative thereupon.

The table or base A is preferably supported by suitable legs or uprights, or as I have shown, by means of the depending flanges a so that the upper or top surface a thereof is disposed in a horizontal plane. The table is preferably rectangular and has formed in its top two parallel series of depressions, or recesses, a^2 , a^3 , a^4 , a^5 , a^6 and a^7 , extending longitudinally thereof. A 40 guide or way extends longitudinally of the table intermediate the two parallel series of depressions, the table and a long flat cover plate a^8 mounted upon the brackets a^9 disposed at each edge of the way and 45 which brackets together with the cover plate, are secured upon the table by means of screws a^{10} . The upper surface of the 50 table functions as the bottom of this guide or way. The sides of the way are open

adjacent the several depressions. A series 55 of vertically aligned transverse slots are formed in the cover plate and the table. The belts pass through the guide or way, and a series of feed rollers a^{11} extend into the transverse slots and feed the belts 60 through the guide. The rollers are disposed in vertically aligned pairs, the lower of which are mounted on the transverse feed shafts a^{12} mounted upon the depending flanges a . The shafts a^{12} have mounted 65 upon them the bevel gears a^{13} engaging the bevel gears a^{14} mounted on the longitudinal or auxiliary drive shaft a^{15} mounted upon the brackets a^{16} extending from the side of the table. The shaft a^{15} is driven from 70 transverse or main drive shaft a^{17} by any suitable means such as the worm a^{18} and the worm wheel a^{19} . The main drive shaft is driven by any suitable means such as a suitable pulley a^{20} and a suitable source of 75 energy, not shown. Above each of the lower feed rolls is mounted a second or upper feed roller having its bearings in the blocks a^{21} slidably mounted between pairs of vertical standards a^{22} . A link a^{23} 80 is mounted atop each pair of standards, and a coil spring a^{24} is mounted intermediate the link and the block mounted on each pair of the standards. The springs retain the upper feed roller in yielding 85 engagement upon the lower feed roller. The upper feed rollers may be driven by means of the gear a^{25} mounted on the forward transverse shaft a^{12} mounted near the front or forward end of the table, and 90 which gear meshes with the gear a^{26} mounted on the shaft supporting the upper feed roller of the first or forward pair of feed rollers. I find that satisfactory results are attained by positively driving the lower 95 feed roller of each pair and the one upper feed roller of the first pair of feed rollers.

The edge rounding mechanism B comprises suitable abraiding wheels or, as I have shown, a pair of circular or disk 100 cutters or knives b , of which one is mounted in each of the depressions a^2 and extends partly therefrom. A suitable bracket b' is pivotally and adjustably mounted on the under surface of the table by any suitable 105 means such as the bolt b^2 adjustably engaging the table and the set screw b^3 adapted to lock the bolt in an adjusted

position. If desired, suitable shims b^4 may be employed to space the bracket from the table. The bracket has mounted upon it the revoluble vertical shaft b^5 , the upper end of which lies within the depression a^2 and has mounted upon it the cutting disks b . A pulley b^6 is mounted on the lower end of the shaft b^5 . The shaft is mounted on suitable ball bearings b^7 . A pin b^8 is 10 adjustably mounted on the depending flange a and a spring b^9 extending between the bracket b and the flange a , yieldingly retains the bracket in engagement with the pin b^8 . The means described permit adjustment of the cutting disks vertically and horizontally in relation to the guide or way on the table. The cutting disks have preferably a central circumferential groove having the shape that is to be given the edge of 20 the belt.

The inking or coloring mechanism C comprises the sleeves c and c' having formed within them vertical bores within which bores are revolubly mounted the shafts c^2 and c^3 respectively. The sleeves c and c' are mounted upon the under surface of the table by any suitable means such as by forming lugs c^4 upon the sleeves and through which lugs the bolts c^5 extend. The shafts 25 c^2 and c^3 extend into the depression a^3 and have mounted upon their upper ends the inking brushes c^6 and c^7 , to which ink is fed from a suitable container c^8 mounted upon the side of the table and having a suitable feed pipe c^9 with a valve c^{10} therein, the feed pipe and valve being adapted to direct and control the flow of ink from the container c^8 to the brushes. The brushes are preferably made of bristles which 30 engage, as shown in Fig. 1. The shafts c^2 and c^3 have mounted upon their lower ends the spiral gears c^{11} and c^{12} respectively, which engage the spiral gear c^{13} mounted upon the shaft c^{14} , mounted transversely of 35 the table and below the upper surface thereof. The shaft c^{14} has mounted upon it the sprocket wheel c^{15} which is driven by means of the chain c^{16} . A pair of brushes as just described, is mounted on each side of the 40 longitudinal way formed over the table.

The burnishing mechanism D comprises the burnishing wheels d of which there are three mounted on each side of the way formed upon the table, one each of such 45 wheels being disposed within the depressions a^4 , a^5 and a^6 . Each of the burnishing wheels is mounted at the upper end of a shaft d' revolubly contained within a sleeve d^2 . The sleeve d^2 has a flange d^3 formed 50 adjacent its upper end, which flange is secured upon the under surface of the table by means of suitable blocks d^4 and bolts d^5 . The blocks d^4 and bolts d^5 are mounted upon the flanges a^{27} formed on the under 55 surface of the table. Sufficient play is pro-

vided between the flanges a^{27} and d^3 to permit any desired horizontal adjustment of the burnishing wheels as shown in Fig. 4. The pulleys d^6 , d^7 , d^8 , d^9 , d^{10} , and d^{11} are mounted upon the lower ends of the shafts 70 d' , the driving of which will be explained hereafter.

The enameling mechanism E comprises a sleeve e mounted upon the under surface of the table and revolubly mounting the vertical shaft e' , the upper end of which shaft extends into the depression a^7 and has mounted on it a brush e^2 , and upon the lower end of which shaft is mounted a spiral gear e^3 . The sleeve e may be mounted upon the 75 table in any suitable manner, such as by means of the lugs e^4 formed upon the sleeve and through which the bolts e^5 extend. The bolts e^5 secure the sleeve upon the table. The slots in the lugs through which the 80 bolts e^5 extend, may be elongated to permit adjustment of the sleeve. A suitable container e^6 for the supply of enamel is mounted upon the side of the table and the enamel is fed therefrom to the brush e by 85 means of a suitable pipe e^7 . The spiral gear e^3 mounted at the lower end of the shaft e^2 meshes with a spiral gear e^8 mounted on the shaft e^9 , mounted below the 90 table transversely thereof. A sprocket 95 wheel e^{10} is mounted upon the shaft e^9 and engages the chain e^{16} . A worm wheel e^{11} is mounted upon the shaft e^9 and engages the worm e^{12} mounted upon the longitudinal 100 drive shaft a^{15} . The sleeves c and c' may be mounted upon the table in the same manner in which sleeve e is mounted in order to permit horizontal adjustment of said sleeves.

Motion is imparted to the shafts b^5 and d' as follows:

The main drive shaft a^{17} has mounted upon it, on opposite sides of the pulley a^{20} , the pulleys a^{28} and a^{29} having the same diameters. A belt f extends about the pulley a^{28} and about the pulley a^{30} mounted adjacent to the pulley d^{10} upon one of the shafts d' . The belt f' extends about the pulley a^{29} and about the pulley a^{31} , mounted adjacent the pulley d^9 on a second shaft d' . A belt f^2 extends about the pulley d^9 , one of the pulleys b^6 mounted upon one of the shafts b^5 , about the pulley d^8 and about the second pulley b^6 mounted on the second shaft b^5 , and then returns to the pulley d^9 . A belt f^3 extends about the pulley d^{10} , the pulley d^9 , the pulley d^{11} and pulley d^7 . The pulleys d^6 , d^7 , d^8 , d^9 , d^{10} and d^{11} are preferably of the same diameter, therefore the 110 burnishing wheels d will revolve at the same rates of speed. The burnishing wheels have a circumferential groove d^{12} , into which the belts extend as they pass through the way. This groove is substantially the same as the circumferential grooves in the cutting disks. 115

The several shafts supporting the cutting 120

disks, the brushes and the burnishing wheels, revolve in the directions indicated by the arrows in Fig. 1.

A casing H is mounted over the cutting disks and has a fan h mounted at one end thereof adapted to withdraw the cuttings from the mechanism B and to discharge the cuttings at any suitable place at a distance from the device.

10 The detailed mounting of the several vertical shafts in the several depending sleeves is shown in Fig. 4.

The operation of my device is as follows:

I will assume that motion is being given 15 to the shaft a^{17} in the direction shown by the arrow in Fig. 2. The shaft a^{17} is mounted at the rear end of the table. A belt G is fed into the way at the front end thereof, and the first pair of feed rollers grasp the 20 belt and feed the same through the way. The feed rollers have motion imparted to them from the shaft a^{15} . As the belt edges are exposed to the cutting disks, the edges of the belt are trimmed or rounded in accordance with the 25 shape given to the cutting tool. The cuttings from the belt are withdrawn through the casing H by means of the exhaust fan h. The belt then passes beneath the second 30 pair of feed rollers and then passes between the inking brushes c^e and c^f , at which time the edges that have been worked upon by the cutting disks are inked. The belt then passes under a third pair of feed rollers, and 35 immediately thereafter is acted upon by two pair of the burnishing wheels d, which burnishing wheels are revolved at a high rate of speed in a direction such that the surfaces of the burnishing wheels engaging the 40 belt edges, move in a direction opposite to

the line of movement of the belt through the way, the friction resulting therefrom serving to dry the ink with which the belt edges are colored. The belt then passes between a fourth pair of feed rollers and is 45 then subjected to a third pair of burnishing wheels moving in the same direction as the preceding burnishing wheels. The fourth pair of feed rollers is interposed between the third pair of burnishing wheels and the 50 second pair of burnishing wheels solely to provide a smooth and even feed of the belt through the way. If desired a larger number of burnishers and feed rolls may be employed. From the last burnishing wheel the 55 belt passes to the enameling mechanism where the brushes e^2 enamel the side edges of the belt. As the belt leaves the rear end of the way, the finishing of the side edges of the belt has been completed. 60

What I claim is:

In a belt trimming device the combination of a table having a way formed in it, means to feed belts thru the way, and belt trimming mechanisms extending into the way 65 and comprising a bracket, a bolt vertically adjustable on the table pivotally supporting the bracket, a bracket having a bearing formed on it, a revoluble shaft carried by the bearing, a cutter carried by the revoluble 70 shaft extending into the way, a pin adjustably mounted on the table engaging the bracket for moving the cutter into the way, and a spring extending between the bracket and the table yieldingly resisting movement 75 of the cutter into the way.

In testimony whereof, I have hereunto subscribed my name this 3rd day of June, 1921.

JAMES D. RANDALL.
